(57) **CLAIM**

We claim the ornamental design for a charging base with dust collector set, as shown and described.

DESCRIPTION

FIG. 1 is a first perspective view of a charging base with dust collector showing our new design;

FIG. 2 is a second perspective view of the charging base with dust collector of FIG. 1 viewed from another aspect;

FIG. 3 is a front view of the charging base with dust collector of FIG. 1;

FIG. 4 is a rear view of the charging base with dust collector of FIG. 1;

FIG. 5 is a left side view of the charging base with dust collector of FIG. 1;

FIG. 6 is a right side view of the charging base with dust collector of FIG. 1;

FIG. 7 is a top view of the charging base with dust collector of FIG. 1;

FIG. 8 is a bottom view of the charging base with dust collector of FIG. 1; and,

FIG. 9 is an enlarged view of portion 9 of the charging base with dust collector of FIG. 1.

The broken lines depict portions of the charging base with dust collector in which the design is embodied that form no part of the claimed design. The dot-dash broken lines encircling portions of the charging base with dust collector in FIG. 1 and illustrated in an enlarged view in FIG. 9 form no part of the claimed design.
